John Nelson

United States Patent Office.

W. W. BURSON AND JOHN NELSON, OF ROCKFORD, ILLINOIS.

Letters Patent No. 79,202, dated June 23, 1868; antedated June 12, 1868.

IMPROVEMENT IN KNITTING-MACHINES.

The Schedule referred to in these Letters Patent and making part of the same.

TO ALL WHOM IT MAY CONCERN:

Be it known that we, W. W. BURSON and JOHN NELSON, both of the city of Rockford, in the county of Winnebago, and State of Illinois, have invented a new and useful Knitting-Machine; and we do hereby declare that the following is a full, clear, and exact description of the same, reference being had to the annexed drawing, forming part of this specification, and to the letters of reference marked thereon.

In the drawing—

Figure 1 is a front perspective view.

Figure 2 is a side elevation.

Figure 3 and 4 shows looper-bearers K.

Figure 5 shows the loop-holding hooks e e.

Figure 6 shows the releasing-lever P.

Figure 7 shows crank L and its attachments.

Our invention has reference to the making of knit fabrics, and consists of certain combinations of devices hereinafter to be set forth.

In the drawing, A supports the loop-carrier B, moving in the groove C, constructed in A. Perpendicular to A is erected the upright, D, fastened to A, which supports gate E, moving in grooved ways F F F F.

Upon the upright, D, is secured the yarn-carrier H, pivoted at I I', as also the crank-shaft J, the turning of which gives motion to gate E, operating in groove Q. The gate E has pivoted to it, at x x', the swinging looper-bearers K, in the slotted, forked ends of which are hung the loopers a a'. Upon the gate E are also secured the reversing-crank L, the trip-rods o o', the depressing-plates 2 2, and feed-lever M.

We construct the loop-carriers e e of two rows of short hooks, placed parallel to each other, the hooks facing outward. These hooks should either be formed by cutting into a solid plate and making them on the edge of it, or they may be made separately, and then fastened together in some convenient manner, in either case allowing the hook to extend about one-fourth of an inch above the edge of the plate B.

Below the hook is formed the groove i, extending about one-third the length of the hook-stem above the plate B, and downward on the plate as far as the looper a is arranged to move.

On the plate B is placed the feed-rack N, for the purpose of moving the loop-carriers, as described, further on.

The looper-bearer K is hinged to gate E at x x', and near its upper end is the groove n, which gives motion to the yarn-carrier H by the pin m moving in said groove.

The crank L, turning in groove P, changes the position of looper-bearer K at each half revolution, when lever P is locked forward, but when thrown backward the crank is allowed free play, the looper-bearer being all the time locked forward.

The loopers a a' are hinged to the slotted end of the looper-bearer K, and are so placed that a shall lift the loops from the hooks e e on one side, and when the crank, L, has been reversed, the looper a' shall act in like manner on the opposite set of hooks. The loopers a a' are not placed opposite each other, but have the same lateral distance between them that there is between the hooks e e.

In regular tubular knitting, the yarn-carrier H' vibrates in the space between the loopers a a', and since the rear looper, with respect to the forward movement of the loop-carriers, is the working one, it will be seen that the yarn-carrier, vibrating as hereinafter described, will always have the yarn in advance of said looper, on whichever set of hooks it may be working.

The looper-bearer swings, so as to work on either side of the loop-carriers e e, and is moved and held in position by the action of crank L turning in slot p. On the opposite ends of crank L are the cross-bars S S', the ends of which are similarly bevelled.

The reversing-rods o o' are held in hollow tubes, surrounded by spiral springs arranged to hold them down, except when forced upward by striking upon the stop-blocks t t', when the upper end of the rod strikes on the

bevelled end of the cross-bar S, and turns it from its working plane, so that the upper end comes against the trip-plate T, when the gate E is raised by the turning of crank J, which movements turn crank L one-half revolution, thereby changing the loopers $a a'$ to the opposite side of the loop-carriers, and with them the yarn-carrier by the action of pin m moving in groove n.

The yarn-carrier H is made in two parts, the piece H being hinged to stationary supports at I I', and connected to the looper-bearer by the pin m moving in groove n, below which connection it is drawn to a spring, and the lower end formed into two notches, in one of which the piece H' of the yarn-carrier is held with reference to lateral movements. Piece H' is pivoted to H at u, the lower end being tubed to hold the yarn in proper position for knitting, and provided with suitable thimbles along its length to hold the yarn in safe position with reference to the other mechanism.

At the ends of the loop-carriers are placed the stop-blocks t t', which are fitted to fill the space between the loop-hooks e e, and are placed near the limit desired to be knitted. When the movement of the loop-carriers brings this block t under the reversing-rod, which has the reciprocating motion of gate E, said rod is raised, whereby the looper-bearer K is changed to the other side of the loop-carriers, as before described.

The feed-bar M is hinged to the gate E at u', and gives motion to the loop-carriers by entering the toothed rack N, below which is the opening V in piece A.

It will be seen that the feed-bar M is constructed so as only to reach the distance of one tooth either way from its central position, which distance corresponds to that of the loop-hooks e e, and having passed through the said toothed rack, is brought to the same central position, whichever side it may have started on, and, of course, must move the loop-carriers the space of one tooth.

To cause the feed-lever M to reach in a particular direction when it is desired to move the loop-carriers in a certain way, and to reach in the opposite direction when the motion of the carriers should be reversed, we secure the spring Y obliquely upon crank-shaft I, the lower end of the spring being held by a staple to the feed-bar M. This oblique hanging of spring Y will give an opposite inclination to feed-lever M at each half revolution of the crank L, thereby reversing the direction of the movements of the loop-carriers by the action of the feed-lever, as just described.

It will be seen that the feed-lever M only moves the loop-carriers while passing the perpendicular distance of the V-shaped sides of opening V, and, having reached the centre of said opening, no further motion will be given to the loop-carriers during the remainder of the movement of the feed-lever until it shall be raised above the rack N and reach out, so as to repeat the movement just described.

The loop-carriers B are constructed with a flange on one side opposite the toothed rack N, which flange and rack keep the carriers from being raised by the action of loopers $a a'$.

The plates B B are also placed somewhat further apart at their lower edges than the upper edges, which construction facilitates the operation of loopers $a a'$, both in the certainty of the looper passing under the loop as also in the ease of lifting it over the hook e.

The construction of groove C in piece A is made to correspond with the shape of loop-carriers B, as just described, whereby they are kept from being raised or tipped sidewise by the action of loopers $a a'$.

The tension-plate z is regulated to make the knitting loose or tight, as desired.

In operating this knitting-machine, the removable bobbin W, with the yarn wound on it, is placed in position, shown in fig. 1, when the end of the yarn is passed through the spring-tension device, through the eyelet and tubed end of yarn-carrier H', and loops having been formed in any convenient manner on the hooks e e, with weight attached to them to hold them down to the edge of plate B, the crank J' is turned, whereby the gate E is raised and lowered by the action of crank J operating in cam-groove Q.

When the gate E is fully lowered, the looper a, being pressed into groove i by the action of spring d, is in position to run under the loop held on hook e, when the gate is raised, by which movement the loop is thrown over the yarn held in yarn-carrier H' and off the hook e, and a new loop formed on the loop-hook, while the tipping of the looper, in its continued upward movement, frees it from the loop just knitted.

When the gate E is fully raised, the feed-lever M is thrown forward the distance of one tooth e' by the spring Y, and passing downward, guided by the opening V, moves the carrier one space of hooks e e, which brings another hook in line with the looper a, when the operation just described is repeated, and this is continued until the stop-block t is brought, by the movement of the loop-carriers, under the reversing-rod o, when this rod, striking the stop-block, is forced against the bevelled end of the cross-bar S, which, thus turned from its working-plane, will take hold of the trip-plate T, and by the continued upward movement of the gate E the crank L will be turned one-half revolution, carrying with it the looper-bearer K and yarn-carrier H, to the opposite side of loop-carriers B. This half revolution of crank L changes the inclination of the spring Y hung obliquely upon the crank-shaft, which changes the direction of feed-bar M, and, operating as before described, will move the loop-carrier in the opposite direction, whereby the looping-mechanism will operate on the opposite side, and in the opposite direction from what it did before reversing, until it brings stop-block t' under the reversing-rod, when the looping-device is again brought to the place of beginning.

It will thus be seen that we knit a continuous tubular fabric on two straight parallel rows of loop-supporters. When it is desired to narrow the fabric, the two end loops are lifted from the end hooks and placed upon the next inner ones, and the block t moved in one space, which may be repeated at both ends of the carrier, which will, of course, reverse the looping-device wherever the stop-block is placed. If the fabric is to be widened, the stop-block must be moved outward, when additional loops will be formed on the hooks e e.

The yarn-carrier H is hinged at I I', and is guided in its movements by the connecting-pin m moving in groove n. Since this groove n is always at a given angle with the plane in which gate E moves, on whichever side it may be working, it will be seen that the yarn-carrier will receive a vibrating motion by the movement of

gate E, the upward movement of the groove throwing it outward and the downward motion bringing it inward. This vibrating movement of the yarn-carrier is such that it is outside the loop-carriers when they are moved forward by the feeding-mechanism, bringing the yarn outside of the loop-carriers. When the loopers descend, the yarn-carrier is moved in toward the centre of the carriers, thereby drawing the yarn tightly against the hook e, and serving also as a sinker when the loop is cast over hook e.

The enlargement shown in groove n gives an irregular movement to the yarn-carrier, allowing it to remain in its sinker position until the loop is cast over hook e.

The operations heretofore described are such as relate to straight tubular work, varied only by widening or narrowing.

When it is desired to knit a flat web on one side only of the rows of loops, the lever P is released from its catch-pin and forced back of the same pin, which locks the looper-bearers forward, and permits crank L to turn freely, but now only changing the feeding-device. The knitting is then done exclusively by looper a, and the yarn-carrier H' must be changed each time the feeding-device changes, so that it shall always be on the front side of looper a, whichever side it shall be moving. This flat web may be widened or narrowed in the same manner as described for tubular knitting.

Our usual manner of forming the heel of hose is by knitting on one side, as described, except that we move the stop-blocks t t' in one or more spaces, without lifting the stitches, until only a few remain near the centre, when we move the blocks out in the same manner, widening each time that we knit across, until arriving at the place of beginning, when we go on with tubular work, as before, a well-shaped heel having been formed.

The depresser-plates 2 2, attached to gate E, pass between the hooks e e' at each downward movement of the gate, forcing the loop down, and insuring the proper working of looper a.

Having thus described our invention, what we desire to secure by Letters Patent, is—

1. The combination and arrangement, with the supporting-frames A D, of the gate E, vibrating yarn-carrier H, and plates B B, provided with loop-carriers e e' e e', and feed-rack N, the whole operating as and for the purpose set forth.
2. The two parallel plates B B, carrying the loop-carriers e e' e e', constructed and arranged to move in the groove C, substantially as described.
3. The combination of yarn-carrier H with looper-bearer K, groove n, and pin m, constructed and operating substantially as set forth.
4. The combination of yarn-carrier H, constructed in two parts as described, with releasing-lever P, loopers a a', and loop-hooks e e'; arranged to knit irregular work, as set forth.
5. The reversing-crank L, in combination with the looper-bearer K, operating substantially as described.
6. The combination of the stop-blocks t t', reversing-rods o o, and loop-hooks e e' e', when constructed and operating substantially as specified.
7. The combination and arrangement of reversing-rods o o, cams s s', and trip-plate T, when constructed and operating substantially as described.
8. The combination and arrangement of the feed-lever M, toothed rack N, and cam-opening V, constructed and operating substantially as described.
9. The combination and arrangement of spring Y, feed-bar M, and crank L, operating substantially as set forth.
10. The combination and arrangement of releasing-lever P, looper-bearer K, and crank L, when constructed and operating substantially as described.
11. Constructing and arranging a knitting-mechanism, substantially such as herein described, so that the reciprocating motion of the gate E shall impart the proper motions to the different parts, substantially as set forth.

W. W. BURSON,
JOHN NELSON.
